UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR ROCK DRILLS.

Application filed April 28, 1923. Serial No. 635,383.

To all whom it may concern:

Be it known that I, LEWIS C. BAYLES, a citizen of the United States, a resident of Easton, county of Northampton, and State 5 of Pennsylvania, have invented a certain Mounting for Rock Drills, of which the following is a specification accompanied by drawings.

This invention relates to rock drills, picks 10 or the like, but more particularly to a mounting therefor.

The objects of the present invention are to produce a mounting from which a rock drill of the pavement breaker type or of 15 the "jackhammer" type may be conveniently suspended in such a manner that the weight thereof is counter-balanced at all times, while permitting the drill to be easily moved to any required location and position in 20 front of the working face, and to any desired distance therefrom without any special adjustment of the mounting. With such a mounting, the drill operator is able to work unhampered by a drill, which is not only 25 heavy but extremely cumbersome.

Further objects of the invention will hereinafter appear, and to all of these ends the invention is shown in one of its preferred forms, in the accompanying drawings, in 30 which—

Figure 1 is a side elevation, of the supporting device with a rock drill attached thereto.

Figure 2 is an enlarged detail view partly 35 in transverse section, taken on the line 2—2 of Figure 1.

Figure 3 is a view in transverse section on the line 3—3 of Figure 1.

Figure 4 is a side elevation of a modified 40 form of my invention, and

Figure 5 is a view in cross section taken on the line 5—5 of Figure 4.

Referring to the drawings, the column A is vertically adjustable on the screw B, 45 which is provided with a screw head C to which is secured the pointer D adapted to bear against the lower wall of the rock, or as in this instance, a block placed thereon. In order to lock the column A from 50 movement relative to the screw B, caused by the vibration set up in the operation of the tool, I provide a key E adapted to be inserted in the jaws or detents F of the column A. A groove G in the screw B 55 forms a guide way for the key E and co-

operates with the jaws or detents for securing the column A from the movement relative to the screw B. A spring clip H suitably secured to the key E encircles the screw B, so that the locking device may be moved up and down and maintained in any desired position. Further details of construction of the column A, are described in my former Patent No. 1,450,709, granted April 3d, 1923.

A pointer J is suitably secured to the upper end of the column A, and is adapted to bear against the upper wall of the rock. For rotating the screw head C to raise or lower the column A, so that the pointers 70 J and D may be forced against the upper and lower wall of the rock respectively, or disengaged therefrom, as desired, I provide holes a in the screw head C into which a bar or rod may be inserted.

A block L is provided with split end portions, which may be tightened on the column A by any suitable means, as by a bolt b and nut c, so that relative movement between the column A and the block L may be prevented. A bar K is pivotally mounted on the bolt b, and in this instance, is provided with a bushing o' for preventing the bolt from pinching on the bar K.

In order to maintain the bar K at right angles to the column A, I provide a latch in the recess e of the block L, having a plunger d and stem d' connected thereto. A coiled spring f in the recess e serves to force the plunger d outwardly, so that the plunger d may enter the aperture g in the bar K thereby holding the bar in the desired position. By moving the head h on the stem d' outwardly, the bar K may be moved downwardly against the column A, 85 as shown in dot and dash lines in Figure 1, so that transportation of the column and bar will be made easier. The bar K can rotate about the axis of the column A with the pointers D and J serving as pivots.

A traveler O, having side plates P and Q, is provided with rollers R mounted in the upper section thereof, to enable the traveler to move freely on the bar K. In the lower portion of the traveler O between the plates P and Q, I mount a plurality of sheaves S and S'. A stop piece T is secured to one end of the bar K for limiting the outward longitudinal movement of the traveler O.

A pulley X having a sheave X' is adapted to be attached to a fluid actuated rock pick having a cylinder a', to which is secured the front head b', adapted to receive the pick steel c' for receiving blows of impact of the hammer piston. The band j surrounds and is secured in any suitable manner to the body of the rock pick Y, and is provided with a pivoted yoke h to which is secured a hook 10 o, attached to the yoke k' of the pulley X.

A sheave V is mounted on the support U on the block L, and serves as a guide for a cable W passing thereover. The cable W, in this instance, is secured at one end of the 15 stop piece T, and passes around the sheave S, sheave X', back around the sheave S' and over the guiding sleeve V as shown. A counter-weight Z, preferably one-half the weight of the tool Y, is adapted to be attached to the outer end of the cable W.

The weight Z serves to counter-balance the weight of the supported tool, so that the operator is not hampered with any excessive weight. The pulley arrangement is such 20 that the weight Z, above described, will be moved twice the distance of the movement of the tool, in either vertical direction.

The rock pick Y can be easily moved vertically below the level of the bar K, and 30 horizontally along the bar, thereby enabling rock drills of the pavement breaker type, or of the "jackhammer" type to be used for drifting or for tunneling work. With my supporting device, the operator is enabled 35 to put his full energy into the drilling of holes, and not in supporting the weight of the drill, as would otherwise be necessary.

In the modification shown in Figure 4, and in the detail view of Figure 5, the block 40 L' is pivotally connected to the column A, so that the bar K may rotate about the axis of the column A. The block L', in this instance, is not split, as in the construction shown in Figures 1 and 2, the tightening of 45 the nut d' on the bolt e' will not have the effect of tightening the block on the column A. Instead of using a pointer for the screw B, I provide a collar C' having claws D' connected to the screw collar C, so that the 50 column A will not turn with the bar K.

I claim:

1. The combination with a column and a bar pivotally connected thereto and rotatable about the axis thereof, means for locking said bar at right angles to the column, said means comprising a latch, of a supporting device for a rock drill comprising a traveler adapted to be moved longitudinally along the bar, means for limiting the outward movement of the traveler, a sheave

mounted on the traveler, a pulley adapted to be attached to a rock drill, a cable secured at one end of the bar, a guiding sheave for the cable, and a counter-balance weight adapted to be attached to the cable, whereby 65 a rock drill may be supported at any desired vertical height below the level of the bar.

2. The combination with a vertically adjustable column, and a bar pivotally connected thereto and rotatable about the axis thereof, means for locking the bar at right angles to the column, of a mounting for a rock drill comprising a traveler adapted to be moved longitudinally along the bar, a 70 sheave mounted on the traveler, means for limiting the outward movement of the traveler on the bar, a guiding sheave, a pulley adapted to be attached to a rock drill, a cable secured at one end to the bar and passing around said sheaves and pulley, and a counter-balance weight, whereby a rock drill may be supported at any desired vertical height below the level of the bar.

3. The combination with a vertically adjustable column, and a bar pivotally connected thereto and rotatable about the axis thereof, means for locking the bar at right angles to the column, of a mounting for a rock drill, comprising a traveler adapted to be moved longitudinally along the bar, a 75 sheave mounted on the traveler, a stop piece for limiting the outward movement of the traveler, a guiding sheave, a pulley adapted to be attached to a rock drill, a cable secured at the outer end of the bar and passing around said sheaves and pulley, and a counter-balance weight adapted to be attached to said cable adjacent the end thereof, whereby 80 a rock drill may be supported at any desired vertical height below the level of the bar.

4. The combination with a vertically adjustable column, a block pivotally mounted thereon, a bar pivotally connected to the 85 block, means for locking the bar at right angles to the column, of a mounting for a rock drill, comprising a traveler movable longitudinally along the bar, sheaves mounted on the traveller, a pulley adapted to be 90 attached to the rock drill, a cable secured at one end of the bar and passing around the sheaves and pulley, and a counter-balance weight adapted to be attached to the cable, whereby the rock drill may be supported at any desired vertical height below the level of the bar.

In testimony whereof I have signed this specification.

LEWIS C. BAYLES.
